(57) **CLAIM**

The ornamental design for a silicone grip for garden tools,
as shown and described.

DESCRIPTION

FIG. 1 is a perspective view of a silicone grip for garden tools showing my new design.

FIG. 2 is a side view thereof;

FIG. 3 is an opposite view thereof;

FIG. 4 is a top view thereof;

FIG. 5 is a bottom view thereof.

FIG. 6 is a front thereof; and,

FIG. 7 is a rear view thereof.

The grip or handle is preferably made of a silicone material.
The garden tool presented in broken lines in FIG. 4 is for
illustrative purposes only and forms no part of the claimed
design.
